UNITED STATES PATENT OFFICE.

HENRY W. GAYS, OF ST. LOUIS, MISSOURI.

DESIGN FOR A CARLINE-POCKET.

SPECIFICATION forming part of Design No. 28,358, dated March 8, 1898.

Application filed January 17, 1898. Serial No. 667,000. Term of patent 14 years.

To all whom it may concern:

Be it known that I, HENRY W. GAYS, a citizen of the United States, residing at the city of St. Louis, State of Missouri, have invented ; a certain new and original Design for Carline-Pockets, of which the following is a full, clear, and exact description, such as will enable others skilled in the art to which it appertains to make and use the same, reference being had to the accompanying drawings, forming part of this specification, in which—

Figure 1 is a view in perspective of my newly-designed carline-pocket as seen from the front, and Fig. 2 is a similar view as seen ; from the rear.

This invention relates to a new and original design for carline-pockets; and it consists, generally stated, in the shape and ornamentation of the pocket, as will hereinafter be described.

In the drawings, A indicates the base, B B the side walls, and C the end wall of the pocket.

The outer ends of the side walls B are ornamented by flanges b, and the end wall C rises somewhat above the pocket proper and then makes a bend or connects to a horizontal portion D, said portion D extending from said end wall C in the opposite direction to that taken by the base A and side walls B B. To the other end of the portion D from that to which the end wall C is connected a portion E connects, and at about right angles thereto, and extends downwardly for a short distance.

Having thus described my new design, what I claim is—

The design for carline-pockets, substantially as herein shown and described.

In testimony whereof I hereunto affix my signature, in the presence of two witnesses, this 8th day of January, 1898.

HENRY W. GAYS.

Witnesses:

F. R. CORNWALL,
HUGH K. WAGNER.
